US0D1076248S

(12) **United States Design Patent** (10) Patent No.: **US D1,076,248 S**
(45) Date of Patent: ** May 20, 2025

(54) **CURVED CAT BED**

(71) Applicant: **Yuechongjia (Chengdu) Technology Co., Ltd.**, Chengdu (CN)

(72) Inventor: **Xin Yao**, Chengdu (CN)

(73) Assignee: **Yuechongjia (Chengdu) Technology Co., Ltd.**, Chengdu (CN)

(**) Term: **15 Years**

(21) Appl. No.: **29/973,981**

(22) Filed: **Nov. 19, 2024**

(51) LOC (15) Cl. **30-06**

(52) U.S. Cl.

USPC **D30/118**

(58) **Field of Classification Search**

(57) **CLAIM**

The ornamental design for a curved cat bed, as shown and described.

DESCRIPTION

FIG. 1 is a front and right side perspective view of a curved cat bed, showing my new design;

FIG. 2 is a rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly dashed broken lines illustrate features of the curved cat bed that form no part of the claimed design.

1 Claim, 8 Drawing Sheets
